UNITED STATES PATENT OFFICE.

ISRAEL EVANS, OF SAN BERNARDINO, CALIFORNIA.

HOSE-COUPING TOOL.

Application filed June 29, 1927. Serial No. 202,335.

My invention is a hose coupling tool for attaching wire to a hose to clamp the hose securely to the coupling.

An object of my invention is the construction of a tool for drawing or clamping wire to a hose to secure same to coupling, and embodies an implement for bending a straight piece of wire forming a pair of eyes and a species of loop. The double ends 10 of the wire are then passed around the hose through the eyes and engaged by my implement to draw the ends tight. In order to effect this, I have a base with a pair of holes therethrough, through which the 15 two ends of the wire may extend upwardly, and rotatably mounted on the base there is a jack screw which has a handle attached thereto. Fitted on the jack screw there is a clamping holder with a pair of perforations therethrough and set screws to engage the free ends of the wire. Hence, on rotation of the handle the jack screw being rotated, separates the clamp on the base, thus pulling tight on the wire until the hose is 20 attached sufficiently tight to the coupling, and after this the tool may be turned to one side, there being a sharp bend or crimp in the wire adjacent the eyes.

Another object of my invention comprises 30 a construction of the tool in which the base provides a mounting for a pair of slideable chisels which may be struck by a hammer and sever the wire adjacent the bend. These severed ends may then be hammered tight 35 against the rubber hose and the wired coupling is completed.

My invention is illustrated in the accompanying drawings, in which:

40 Figure 1 is an elevation of my hose coupling tool with the connection partly completed, and also illustrating a completed joint.

Fig. 2 is a vertical section on the line 2—2 of Figure 1 in the direction of the arrows.

45 Fig. 3 is a perspective view of the tool.

Fig. 4 is a diagram of part of the tool showing the manner of bending the wire to form the two eyes and a loop.

50 Referring first to the manner of making the loop. This is effected by utilizing the handle 11 of the tool, which has a pair of pins 12 extending upwardly therefrom. The wire to form the binding or tie for the coupling is preferably formed of a straight section in which one part 13 is placed 55 against the pins 12 and parallel to the han-

dle 11. The wire is then given a twist or bent around the pins forming a pair of eyes 14 with the wire portion 15 passing over the part 13. The wire so bent is so removed 60 from the pins 12, and the portions 16 of the wire may then be bent around a hose and the ends 17 pass through the eyes 14. The further details of securing the wire to the hose is substantially as hereunder given. 65

The tightening features of the tool comprise a base 18 which is preferably a rectangular block and has a pair of openings or apertures 19 extending therethrough, and it is through these apertures that the ends 70 17 of the wire are inserted. Secured to the base there is a jack screw 20 which preferably has a head 21 fitted in a socket in the base, retained therein by a set screw 22. With this construction the jack screw is free 75 to rotate relative to the block, and may be manipulated by the handle 11.

The wire clamp 23 comprises a rectangular block-like structure 24 with a pair of apertures 25 therethrough, and set screws 26 80 are threaded in the ends of the block. When the wire is passed upwardly through the apertures 25, the set screws may be jammed against the free ends of the wire and then the handle is rotated, which separates the base and the clamping part of the tool, this action putting a tensile stress on the wire and pulling it tight in engagement with the hose and a coupling designated by the numeral 27. 85

When the wire is tightened to a sufficient extent, the implement is turned to one side in the direction of the arrow 28 as shown in Figure 2, which gives a sharp angular bend 95 in the wire adjacent the eyes 14. The wire is then severed in the following manner.

A pair of cold chisels 29 are slidably mounted in bores 30 in the base 18. Each chisel has a head 31 which is engaged by a compression spring 32 fitted in an enlargement of the bore, thus normally tending to maintain the chisel in its outward position, and each of the chisels is restricted in its movement by a stop screw 33 which is threaded through the top of the block forming the base and engages in an elongated notch 34 in each of the chisels. After the wire has been bent to one side in the manner described, the heads 31 of the chisels may be struck by a hammer, thus severing the wire held in the clamp 23 from the wire loop around the hose. The ends 35 of the wire forming the loop are 100 105 110

then hammered into the hose and preferably hammered close to the portion of the wire 16 which encircles the hose.

- From the above description it will be seen
5 that I have developed a comprehensive hose
coupling tool which may be utilized to bend
the wire into shape suitable for use as a hose
clamp in connection with the coupling, and
that the implement is arranged to draw
10 tightly on the wire, thus forming a tight con-
nection between the coupling and the hose,
and then subsequently to sever the wire after
bending in proper position for finally secur-
ing it in position.
15 Various changes may be made in the prin-
ciples of my invention without departing
from the spirit thereof, as set forth in the
description, drawings and claims.

I claim:

- 20 1. A hose coupling tool having a block
forming a base with an opening vertically
therethrough, a jack mounted on the base, a
clamp on the jack to engage a wire extend-
ing through the opening in the base, means
25 to operate the jack to separate the base and
the clamp and exert a tension on the wire, the
base having a bore at right angles to the said
opening, and a cold chisel operating in said
bore adapted to sever the wire fastened
30 through the opening in the base.
2. A hose coupling tool comprising in com-
bination a block forming a base with a ver-
tical aperture therethrough, a screw jack ro-
tatably mounted on the base and extending
35 vertically upwardly, a clamp threaded on the

screw jack and having means to engage a
wire passed upwardly through the aperture
in the base, the jack on rotation separating
the base and the clamp and exerting a ten-
sion on the wire, the jack and base being 40
tiltable to one side to form a bend in the
wire below the base, the said base having a
lateral bore, a cold chisel slidably mounted
therein, a spring normally thrusting the cold
chisel outwardly, and means to retain the 45
cold chisel in the bore, the said cold chisel
being adapted to cut a wire extending
through the aperture in the base.

3. A hose coupling tool comprising in com-
bination a rectangular block forming a base 50
and having a plurality of vertical openings
therethrough, a screw jack having its lower
end rotatably mounted in the base between
the said apertures, a clamp threaded on the
screw jack having a pair of apertures there-
55 through, set screws in the clamp to engage
wires in the apertures of the clamp, such
wires being passed upwardly through the
apertures in the base, a handle to rotate a
screw jack and separate the base and the
60 clamp, thereby exerting a tension on the
wire, the base and the jack being tiltable
to form a bend in the wire, and a pair of
cold chisels slidable in bores at right angles
65 to the openings therethrough, each of said
cold chisels being adapted to sever a wire in
one of said openings.

In testimony whereof I have signed my
name to this specification.

ISRAEL EVANS.
